UNITED STATES PATENT OFFICE.

LOUIS G. FREEMAN, OF CINCINNATI, OHIO, ASSIGNEE TO LOUIS G. FREEMAN AND CHARLES F. FREEMAN, TRUSTEES, BOTH OF CINCINNATI, OHIO.

HEEL-BREAST-TRIMMING MACHINE.

1,354,037.

Specification of Letters Patent. Patented Sept. 28, 1920.

Application filed June 15, 1917. Serial No. 174,824.

To all whom it may concern:

Be it known that I, LOUIS G. FREEMAN, a citizen of the United States, and resident of Cincinnati, in the county of Hamilton 5 and State of Ohio, have invented an Improvement in Heel-Breast-Trimming Machines, of which the following description, in connection with the accompanying drawings, is a specification, like letters on the 10 drawings representing like parts.

My present invention is an improved machine to trim or cut the heel breasts of boots and shoes, particularly the curved heel breasts such as Louis heels, half-Louis heels, 15 and the like. Such heels are made in a wide variety of curving breast portions, particularly where the heel is joined to the shank, and this curved portion presents an unusually difficult surface to be cut. The prior 20 machines using straight heel breasting knives could not be employed on Louis heels, excepting possibly for a very short distance from the toplift inwardly until the curved portion is reached. As the trimming 25 of such heel breasts by hand was an extremely difficult, expensive and unsatisfactory method, several attempts have recently been made to develop a machine for doing such work, but which have not fulfilled the 30 requirement or possessed a range to meet the wide variety of Louis heel breast styles nor for rapid commercial work. It is an object of my present invention to provide novel means to hold and support the shoe; to employ removable guards or templets secured 35 on the shoe jack adjacent the heel to cooperate with means adjacent the cutting tool to control the relative movement between shoe and cutter in any desired curve or line; 40 to improve the heel supporting jack and clamp; to provide an automatic guard between the cutting tool and shoe, to prevent any injury to the shoe; and various features of adjustment.

45 A specially important feature in my present machine consists in the arrangement of the cutter, the adjacent guards for the templets to control the curve or line of cut on the heel breast, and the exhaust pipe 50 so arranged with relation to the cutter as to

constitute a guide or guard for the shoe shank, preventing the cutter from marring the shank, while permitting the completion of the cutting or trimming action on the curved heel breast directly up to the shoe 55 shank and the relative rocking movement of the shoe and cutter to permit trimming the heel breast at each outer edge of the heel to a pattern. This combined dust hood and guard enables the machine to trim the 60 curved heel breast right in to the joint between the breast and the shoe shank, particularly in the full Louis or half-Louis type of heel, entirely eliminating any hand work and finishing the heel in this particular at a 65 single operation.

Another object of the invention is to provide jack devices for holding the shoe and for presenting the parts to be trimmed properly to a rapidly rotating cutter, in which 70 the work under universal motion can be moved to and from the cutter, in a direction tangent to the cutter for feeding the work as it is being trimmed, and sidewise for edge rounding, with all the motions guided for 75 producing a predetermined finish of heel and limited or guarded to prevent injury to the shoe. My improved machine eliminates the services of a skilled operator and enables the work to be accurately and rapidly done 80 with ease and convenience for increasing the capacity, producing higher quality of work and uniformity in the finished product.

Additional features of the invention, novel combinations of parts and details of 85 construction will be hereinafter more fully pointed out and claimed.

Referring to the drawings illustrating a preferred embodiment of the invention, like characters of reference denote corresponding 90 parts throughout the several views, of which:

Figure 1 is a front view of my improved heel breasting machine.

Fig. 2 is a side view looking from the left 95 of Fig. 1.

Fig. 3 is a side view looking from the right.

Fig. 4 is an enlarged side view of the jack and cutter mechanism, shown partly in cross- 100

section, corresponding to the position of Fig. 2.

Fig. 5 is a front elevation of the jack in an elevated position with a modification of 5 some of the parts over that shown in Figs. 1 to 4 inclusive.

Fig. 6 is a detail view of the rotary cutter, showing in dotted lines movements of the shoe relative to the cutter.

10 Fig. 7 is an enlarged detail view of a portion of the heel clamp and templet.

Fig. 8 is a rear view of the parts shown in Fig. 7.

15 Fig. 9 is a view similar to Fig. 4 showing the shoe holding jack in elevated position.

Fig. 10 is a side view of an exhaust snout and cutter guard.

Fig. 11 is a front view thereof.

20 Fig. 12 is a detailed section on line 12—12 of Fig. 5.

As the use of the machine is principally for trimming heel breasts of boots and shoes and particularly to a class of heels known as Louis or half-Louis heels of ladies' wears, 25 in which the breast follows a straight and curved configuration developing into a curved line meeting with the shank of the shoe, and in which the side edges of the heel at the shank are rounded, the description 30 of the machine as to its mode of operation will be confined to such particular use.

The shoe, sole and heel upward, is clamped at the heel upon a jack with the toe of the shoe engaged upon an adjustable toe rest 35 carried by the jack, the jack normally occupying a position forward and downward from a rotary cutter, locating the parts for convenience to the operator, so that he can quickly insert and remove the shoe from 40 the jack, and freely operate the various parts so that the work can be performed with speed and accuracy.

The jack is arranged to provide for universal motion, rearwardly and upwardly toward the cutter for presenting the heel to the cutter and also to be moved sidewise to swing the shoe in an arc for a rounded finish at each side, of a shoe bisecting line drawn from heel to toe. The jack, after the shoe 50 has been clamped thereon, is moved toward the cutter, and its limits of motion are controlled by guard and templet devices to trim the heel breast to conform to a predetermined configuration.

55 Referring to Figs. 1 and 2 of the drawings, 1 indicates the base of a column 2 upon which the various parts are mounted and journaled. The upper portion of the column is of yoke design providing two 60 spaced arms furnishing bearings for the cutter shaft 3, over arm or bar 4 which supports an exhaust snout for carrying off the trimmings, and a second shaft 5 as a counter-shaft for grinder devices used in sharpening the cutter on shaft 3.

A shaft 7 journals in bearings formed at the base of the column provided with a pulley 8 having a belt 9 connecting with a pulley 10 fixed upon the cutter shaft 3. Transmission devices for controlling the rotating of the shaft 7 are shown in Fig. 1 70 comprising a tight and loose pulley 11—11, a belt 12, and a belt shifter 13, which, however, may be of any commercial design or type. 75

A grooved pulley 14 is fixed upon the shaft 7 belted to a pulley 15 on the grinder counter shaft 5 for rotating the grinder device 16. The grinder devices are arranged to swing and bring the grinder wheel into 80 coöperation with the cutter. But, as the grinder devices are auxiliary to the machine no detail description thereof is made herein. The machine may also include other shoe or heel finishing devices as auxiliaries 85 to the heel breasting devices and as is included in the drawings, Figs. 1 to 4, transmittingly connecting with the cutter shaft 3, but as they do not form a part of this invention description thereof will not be 90 included.

One end of the cutter shaft 3 projects beyond the bearing yoke of the column, to which a cutter 18 is fixed. This end of the shaft 3 is provided with a journal strap 19 95 connecting said shaft with the over arm or shaft 4. The strap or arm 19 has a sleeve at each end for respectively receiving the shaft 3 and the shaft or rod 4. The sleeve engaging with the rod 4 is split to enable 100 it to be frictionally clamped to the rod 4. The strap stabilizes the cutter shaft 3 against vibratory motion when revolved at the high rate of speed necessary or essential to the cutter for making a clean cut. 105

Cutter.

The cutter 18 as shown in Fig. 4 represents a type having removable cutter blades, while as shown in Fig. 9 the cutter has its 110 cutting edge formed integral therewith, and this latter form is the more preferable as the diameter of the cutter is standardized for a determined radius of heel breast curve at the juncture of heel breast and shank, 115 using a different diameter cutter for each different radius of heel breast curve, and to the trade offers many advantages over a removable blade type of cutter, it being regarded that the shoemaker as a rule does not 120 possess the skill of a mechanic to make the necessary machine adjustments. The cutter is shown as of double cutting edge type with the cutting edges diametrically disposed and of a selected diameter to give the 125 proper degree of curve at the base of the heel breast where it joins with the sole shank portion of the shoe as disclosed in Fig. 9. The breast portion of the heel is trimmed to any angle or line desired or as may be 130

regarded as proper in the shoe cut relative to swing of last or shoe, by a movement of the work in a direction parallel with a diametric line through the cutter so that the

5 work is brought tangent to the rotation of the cutting edges and such trimming may be either in a straight, curved or irregular line depending upon guide or cam outline of templets attached to the jack to be herein-
10 after described.

The cutter is removed by loosening and disengaging the shaft brace strap 19 from the end of the shaft 3, and sliding the cutter endwise of the shaft. The brace strap 19
15 is easily adjusted and centered with the shaft axis and alined with the shaft bearings upon the column.

Universal motion shoe supporting jack.

20 20 indicates a counterweight jack supporting and actuating lever pivotally mounted within a girdle bracket 21 fixed to and longitudinally projecting from the column 2. The rear end of the lever is
25 provided with a weight 22 to counter-balance the weight of the jack devices supported upon the forward end of the lever. The downward swing of the forward end of the lever 20 is limited by a stop screw
30 23 threaded through a lug 24 projecting laterally from the bracket 21. (See Figs. 4 and 9.) A pair of arms 25 project from the forward end of the lever 20 to and between which a rocking jack cradle 26 is
35 pivotally supported. This cradle is of curved form, extending upwardly from its fulcrum, and provides a swived support for the rocking jack 27. The rocking jack 27 conforms to the shape of the cradle 26 and
40 is capable of being swung to the right or left independent of the cradle and with the cradle as a unit forward and backward upon the lever 20, and the jack 27, cradle 26 and lever 20 move as a unit in presenting the
45 shoe heel to the action of the cutter. The unitary motion of jack 27 and cradle 26 provides for bringing the parts forwardly upon the lever and away from the cutter to a position where the shoe can be freely
50 applied upon the jack or removed. The swinging jack members 26 and 27 are locked in such normal position forward upon the lever 20 and must be released before the shoe upon the jack can be moved to bring
55 its heel against the cutter.

A latch lug 28 is formed integral with and projects upwardly from the forward end of the lever 20. This lug 28 is engaged by a spring tensioned latch bolt 29 slidably
60 mounted within a groove in the casing plate 30 secured upon the front face of the arched bearing plate 31 fixed to the rocking jack 27. The arched bearing plate 31 rides or slides upon a curved track plate 32 fixed
65 upon the front end of the cradle 26. The

bearing plate 31 and track plate 32 support the forward end of the rocking jack and provide stops to limit the rocking motion of the rocking jack 27.

As will be seen from Fig. 5, lugs or washers are secured to each end of the bearing plate 31, which project from said plate sufficiently to alternately engage with the respective ends of the track plate 32. The lock bolt 29 is located central with the rocking jack 27 and thus serves to center the rocking jack upon its cradle 26 when the parts are in their normal position. 75

The lock bolt 29 has a pin 33 fixed thereto and projecting from each side thereof. The forward end of the pin 33 is engaged by a trip lever 34 pivotally mounted upon the forward face of the bearing plate 31 of the rocking jack 27. The rear end of the pin 33 is adapted to alternately engage into the notches 35, 36, (see Fig. 1), formed respectively in the bearing plate 31 and track plate 32 and provides the means for centrally connecting the rocking jack 27 and cradle 26 and locking jack 27 upon the cradle 26 against sidewise swing. The latch bolt is therefore utilized for locking the jack 27 and its cradle 26 against forward and rearward swing upon the lever 20 and the rocking jack 27 against sidewise motion upon its cradle, and also serves to relatively center the parts. The notches 35, 36, are located in their respective members at a point central with the jack and cradle and the notch 36 in the cradle is of a depth to permit sufficient upward motion of the latch bolt 29 to unlatch the cradle from the lever 20 without unlocking the rocking jack. The cradle and jack can thus be swung rearward until the abutment 37 projecting from the cradle engages or rests upon the lever 20, when the parts are in position to be moved toward the cutter. A treadle 38, mounted at the base of the column, connects with the lever 20 through 100 a link 39 for raising the lever 20. 105

After the heel breast has been trimmed, the shoe may be rocked to the right or left for trimming the edges of the heel and sole at the shank by moving the latch bolt 29 upwardly its limit of throw, disengaging the pin 33 from the notch 36 in the cradle and bringing the pin into registry with the notch 35 of the rocking jack. The jack and cradle must be brought into a relatively 110 central position before the jack can be locked to the cradle which always insures bringing the parts to their proper position for trimming the heel breast. 115

Toe rest.

At the swivel end of the rocking jack, I provide an adjustable toe rest moving in a direction parallel to the axis of the pivot pin 40 connecting the rocking jack 27 to the 120 130

cradle 26. The toe rest comprises a member 41 having a saw toothed rack extension 42 sliding within the guide plate 43. The guide plate 43 straddles and is fixed to the 5 end of the rocking jack 27. The teeth of the rack extension 42 engage with the teeth of a rack plate 44 fixed to the jack 27 and an adjustment of the toe rest is made by raising or tilting it sufficiently to disengage the rack 10 teeth of the rack member 42 from the teeth of the rack plate 44 and then sliding the toe rest in or out as desired and when again brought to a horizontal plane is reengaged with the rack plate. The upward face of 15 the toe rest or member 41 is dove-tailed to receive the toe pad 45 against which the toe portion of the shoe bears when the shoe is clamped upon the jack.

The rocking jack is provided with an adjustable post member engaging with the last 20 of the shoe and comprises the following elements:

46 indicates the head of the post having a screw threaded shank portion 47 extending 25 into the nipple 48 integral with and projecting from the free end of the rocking jack 27. The nipple intermediately is notched to receive the nut 49 engaging the screw 47 for adjusting the head of the post to different 30 elevations. '49' indicates a dowel pin fixed to the head and slidably fitting into a bore in the nipple 48. A jack pin block 50 is hingedly mounted upon the post head 46 having a pin 51 projecting therefrom, 35 adapted to engage into a socket or bore in the shoe last. The pin block 50 has a lug extending at right angles therefrom, providing a moving abutment for the spring 52 seating within a bore in the head 46. The 40 spring urges the pin block toward the head and provides a yielding coupling for connecting the shoe last to the jack post, enabling the lasted shoe to be swung to bring the toe of the shoe upon the toe rest and 45 forcibly hold the toe of the shoe upon the rest.

Heel clamp.

After the shoe has been mounted upon the 50 jack post with its toe engaged upon the toe rest, the heel is engaged by a clamp which securely holds the shoe upon the jack. The setting of the clamp edge with relation to the breast edge of the heel governs the 55 amount of material to be trimmed off of the heel breast. Thus the clamp also qualifies as a gage which enables the heels to be uniformly trimmed.

The clamp consists of a pair of rack arms 60 53, 53, one mounted and hinged upon each side of the forward end of the rocking jack 27. These arms 53 engage into ways formed in the clamp frame 54, adapting the frame to be moved longitudinally upon said arms. 65 The clamp frame 54 supports and journals

a pinion shaft 55 with the pinion teeth respectively meshing with the teeth of the rack arms 53, whereby when the shaft 55 is rotated the clamp frame may be moved upon the arms in either a heel clamping or releasing direction. A cover plate 56 forming a closure for the right rack arm 53 is secured to the clamp frame, and is provided, integrally, with a cylindrical casing portion 57 which has ratchet teeth formed upon its inner periphery adapted to be engaged by a pawl 58 pivotally mounted in the hub portion 59 of the clamping lever 60 fixed upon the end of the pinion shaft 55. In practice for convenience of manufacture, the ratchet teeth are cut upon the inner periphery of a ring which is fitted and secured within the annular flange of the casing 57.

The pawl 58 has a stud projected therefrom which has a bearing in the clamping 85 lever, bringing the stud upon the exterior side of the clamping lever to which a pawl lever 61 is fixed. The pawl lever 61 extends in a direction parallel with the handle portion of the clamping lever 60 adapting the 90 pawl to be released for freely rotating the pinion shaft in any direction when either releasing or clamping the heel. This clamping lever and its shaft can be adjusted so as to always bring the handle to a most convenient position for the operator, and which adjustment is made when the work is changed from one size of heel to another. The pawl locks the pinion shaft against motion in a clamp releasing direction, so 95 that the clamp can be brought down upon the heel under any desired pressure and retained in its clamping position. The left end of the pinion shaft 55 projects slightly beyond the clamp frame 54 to receive a 100 spring 62 engaged between a washer, forming a head for the shaft, and the clamp frame for urging the shaft longitudinally and enabling the shaft to be slid toward the right for disengaging its pinions from the 105 rack arms 53 for adjusting the position of the clamp lever 60. The clamp frame 54 is provided with a handle 63 which is grasped by the operator for swinging the heel clamp over or away from the heel, and also for 110 rocking the jack 27 sidewise in trimming the heel breast edges and shank portions of the shoe.

A jaw block 64 is mounted within the clamp frame 54 and pivotally secured to the 115 frame by a pair of screws 65, one engaged into the block from each side. The jaw block 64 is provided with upwardly and laterally projecting arms 66 which lap over the ends of the clamp frame to receive the 120 templet plates 67, 67. The templet plates each respectively engage with a screw 65 as a fulcrum for swinging the templet to adjust its position relatively to the jaw block. Each templet is provided with a curved slot 125 130

68 through which a screw or pin 69 engages for securing the templet to an arm of the jaw block.

As shown, the templets are coupled together by a connecting rod 70 to insure uniform adjustment, one with the other. These templets are each provided with a cam or guiding edge 71 which governs the pitch of heel trim or vertical outline of the heel 10 breast, which may be either straight or curved and also limit the amount of material to be trimmed off of the heel breast. The guiding edges 71 of the templets engage against rollers 72 sleeved upon the bearings 15 of the cutter shaft 3 and concentric with said shaft, thereby limiting the movement of the jack toward the cutter. In Fig. 9 a straight edge templet is shown, engaging a roller 72.

The jaw block 64 at its upper side is provided with a dove-tailed groove into which is slidably fitted the shank portion of a heel stop plate 73. This stop plate 73 is secured to a screw 74 threaded into the block 64 for adjusting the curved heel engaging 25 portion 75 of the plate toward or from the front of the jaw block.

As shown in Fig. 9, the portion 75 of the heel stop plate 73 engages the rear of the heel and thus serves as a gage for properly 30 setting the clamp and its templets so that no skill is required in producing uniformity in the work when trimming a lot of shoes of the same size and style of heel. The lower face of the jaw block 64 is provided with a 35 roughened or serrated plate for firmly gripping the face lift of the heel when the shoe is clamped within the jack.

Exhaust hood or snout.

40 77 indicates an exhaust hood or snout adjustably secured to the rod or over arm 4. This snout has a rear tubular portion to which the exhaust conductor piping is connected, and from the tubular portion is developed into a rectangular conduit portion, with its lower wall curved at its extremity, forming a guard 78 to partially shield the cutter, as shown in Fig. 9, and against which the sole of the shoe at the shank is 45 brought to limit the upward motion of the jack, making it impossible to cut into the sole at the shank. The snout is mounted upon a bracket arm 79 and is adjustable with said arm in a direction radially with 50 respect to the diameter of the cutter and also upon the arm in a direction toward and from the cutter. The bracket arm 79 is provided with a sleeve through which the over arm or rod 4 projects, and upon which the 55 arms swing. The sleeve is split toward one end for frictionally clamping the arm to the rod 4. A screw 80 engages through ears projecting from the sleeve at its split portion providing clamping means.

60 65 A clevis or eye bolt 81 is pivotally mount-

ed upon the frame of the machine with its bolt end engaging through the arm 79 and carries a nut 82 for adjusting the arm pivotally upon the rod to bring the guard 78 to its proper position about the cutter. The 70 bolt also carries a spring 83 pressing against the lower face of the arm to urge the arm in an upward direction and assist in making an adjustment. The snout has a plane upper wall which bears against the lower 75 face of the bracket arm, and is provided with a pair of lugs 84, 85, lug 84 projecting through a slot 86 in the arm 79 and carrying a set screw 86' for securely fastening the parts together. Lug 85 carries a set screw 80 87 extending at right angles thereto and having a threaded engagement with a threaded bore in the sleeve portion of bracket arm and provides for a micrometer adjustment of the snout in a direction toward or from the cutter. Thus an adjustment of the snout in one direction is made by adjusting the snout upon the bracket arm 79 by turning the screw 87 after which the parts are locked together by the set screw 86' and the second adjustment is made by the nut 82, to swing the bracket arm upon the over arm or rod 4.

Cutter guard.

95

In machines having a rapidly revolving cutter it is a requirement in many states and localities that said tools be protected with proper guards to prevent injury to the operator. To fulfil such requirement, I provide foldable guards comprising two curved plates 88, 89, hingedly connected together under spring tension and arranged to fold toward each other so as to automatically envelop the cutter, as shown in Fig. 4.

105

The plate 88 has a pin 90 projected beyond both of its side edges, and the hinge pin 90' similarly projects laterally so that both pins engage and ride over the roller sleeves upon the cutter shaft bearing between which the cutter is disposed. The pins 90—90' guide the plates around the cutter and free from contact with the cutter. The plate 89 is hingedly mounted between the spring actuated levers 93 connected as a unit and pivoted to the bracket 21. These levers are engaged by a rod 91 projecting from the side of the cradle, so that the guard is moved automatically with the motion of the cradle. The guard plates 110 88, 89 are arranged so that the pins 90—90' first travel around the roller sleeves and subsequently upon a rail 92 formed upon the lower face of the exhaust snout which guides the plates from and toward the cutter. (See 115 Fig. 9.)

120

125

Mode of operation.

With the jack parts in their normal position as shown in Figs. 2 and 4, but with the 130

heel clamp swung rearward to rest upon the stop rod 94 projecting forwardly from the jack, it will be recognized that all the parts occupy a position which makes it very convenient to apply the lasted shoe upon the jack post, and bring the toe upon the rest. The shoe can be shifted, slightly moving the toe either to the right or left upon its rest, so that the cutter will trim the heel breast 10 at a proper angle relative to the swing of the last or shoe. That is, the trimming crosswise of the heel will either follow at right angles or at an obtuse angle to a line drawn from the center of the toe of the 15 shoe to the heel and appropriately in the latter instance for a right or left shoe, in degrees to meet the fashion of the various manufacturers. With the shoe properly located within the jack the heel clamp is 20 brought upward with the clamp jaw engaging over the heel to a limit permitted by the jaw heel stop, a proper adjustment of the stop having been made. The manner in which the various adjustments are made 25 have been previously made clear when describing the parts, so that it is not necessary to again allude thereto.

It is therefore assumed that the lasted shoe has been properly positioned and 30 clamped within the jack and ready for trimming the heel. The handle 63 is grasped with one hand by the operator and with the other hand the lever actuating the latch bolt is moved to release the bolt from its 35 engagement with the lug upon the lever 20, and the jack members 26, 27 are swung to a reclined position upon said lever 20. This step in the operation is necessary, otherwise it would be impossible to swing the 40 shoe beneath the cutter. Now with the aid of the treadle, the lever 20 and jack members are swung upwardly, the jack members swinging upon said lever to engage the templet against the cutter bearing rollers. 45 The operator applying pressure through his hold upon the handle 63, retains the templet engagement with the rollers during the continued upward movement of the jack while trimming the heel breast. The jack is 50 moved upward until the shank of the shoe engages the guard at the end of the exhaust snout, which finishes the trimming operation unless the edges of the heel are to be rounded or trimmed. If such edge trimming 55 is desired, the operator continues to hold the jack in its uppermost position and releases the rocking jack from the cradle and then rocks the jack to one side and then to the other side, holding the templet firmly 60 against the guide rollers and the shank of the shoe against the stationary cutter guard of the exhaust snout. This side or rocking movement of the jack will trim the curved portion at the juncture of heel and 65 sole to a design conforming to the shape of

the shank from edge to edge. After edge trimming or rounding, the jack is again brought to a central or alining position with the cradle and locked, treadle pressure is then released and the parts are drawn to 70 their normal open position.

With the templets mounted upon the heel clamp, and swinging as a unit therewith when the clamp is secured to the face lift of the heel, the templets will be set to 75 a relation with the plane of the heel lift, and therefore the breast will be trimmed along a line which bears a relation to the plane of the heel face lift, automatically producing the finish much sought by shoe 80 makers. Thus if the face lift of the heel is slightly inclined the heel breast trimming line from lift to shank will be at a different pitch than if the face lift follows a straight line. The heel breast pitch or its 85 line of trim will always bear a relation to the line of trim of the rear portion of the heel which likewise is gaged by the line of the face lift; thus symmetry is produced between the various finish lines of the heel. 90

It will also be appreciated that an important feature is the arrangement of the jaw block 64, being pivoted so that as the same is brought into engagement with the toplift or face-lift of the heel, it automatically adjusts itself to the plane of the heel, and exerts a uniform pressure on the entire heel automatically. This arrangement also avoids straining either the heel or the shoe, as would be the case if the clamping frame 100 54 and jaw block were solidly and rigidly connected so as always to effect a clamping action on a fixed plane.

Having described my invention, I claim:

1. In a machine of the class described, 105 adapted to trim the heel breasts of boots and shoes, a rotary cutter, a rocking frame, a movable jack carried thereby and adapted to hold a shoe, means to adjust said jack so that the heel breast is presented to the cutter in a predetermined angular position to clear the shoe shank, and means to move the jack and shoe toward and from said cutter in said angular position while thus adjusted.

2. In a machine of the class described, 110 adapted to trim the heel breasts of boots and shoes, a rotary cutter, a rocking frame, a movable jack carried thereby and adapted to hold a shoe, means to adjust said jack so that the heel breast is presented to the cutter in an angular position to clear the shoe shank, guides on said jack to control the trimming operation, and means to move the jack and shoe toward and from said cutter 115 while held in said angular position.

3. In a machine to trim the heel breasts 120 of boots and shoes, a rotary cutter, a jack to hold a shoe, means to adjust said jack to present the heel breast to said cutter in the 130

line of a predetermined angular movement, means to move the jack toward and from said cutter in said angular line and counterbalancing means for said jack movable 5 with the jack in said angular line.

4. In a machine to trim the heel breasts of boots and shoes, a rotary cutter, a jack to hold a shoe, means to adjust said jack to present the heel breast to said cutter in the 10 line of a predetermined angular movement, means to guide said jack relatively to the cutter, and means permitting the shoe holding portion of said jack to be oscillated relatively to the cutter, whereby the shoe is 15 alined with said cutter by the said guiding means.

5. In a heel breasting machine of the class described, a rotary cutter, a guard for said cutter, means to guide a shoe upon said 20 guard during the trimming operation, a jack having provision to hold a shoe and to automatically aline said shoe with respect to said guard and cutter, together with a slide carrying said jack, means to balance the 25 jack in any of its positions on said slide and means to move said jack toward and from the cutter at any point on said slide.

6. In a heel breasting machine of the class described, a rotary cutter, a guard for 30 said cutter, means to guide a shoe upon said guard during the trimming operation, a jack having provision to hold a shoe and to automatically aline said shoe with respect to said guard and cutter, together with a 35 slide carrying said jack, means to balance the jack in any of its positions on said slide and means to move said jack toward and from the cutter at any point on said slide, with substantially the same degree of feed- 40 ing movement.

7. In a machine of the class described, adapted to trim the heel breasts of boots and shoes, a rotary cutter, and a jack mounted for swinging movements in planes at right 45 angles to each other adapted to hold a shoe exposing the heel and sole, and means to guide said jack for presenting the heel breast to the cutter in predetermined position.

8. In a machine of the class described, adapted to trim the heel breasts of boots and shoes, a rotary cutter, a jack mounted for swinging movements in planes at right angles to each other adapted to hold a shoe 55 exposing the heel and sole, and for presenting the heel breast to the cutter, and a stationary guard partially covering said cutter against which the shank of the shoe is brought to limit a motion of the jack in a 60 work feeding direction.

9. In a machine of the class described, adapted to trim the heel breasts of boots and shoes, a rotary cutter, a jack mounted for swinging movements in planes at right 65 angles to each other adapted to hold a shoe,

and a templet defining a line of heel breast trim mounted on said jack for limiting and guiding the movement of the jack relative to said cutter.

10. In a machine of the class described 70 adapted to trim the heel breasts of boots and shoes, a rotary cutter, a jack mounted for swinging movements in planes at right angles to each other adapted to hold a shoe, having a yieldable post to receive the last, 75 and a rest to receive the toe of a lasted shoe.

11. In a machine of the class described, adapted to trim the heel breasts of boots and shoes, a rotary cutter, and a jack mounted for swinging movements in planes 80 at right angles to each other adapted to hold a lasted shoe for presenting the heel breast to the cutter.

12. In a machine of the class described, adapted to trim the heel breasts of boots and 85 shoes, a rotary cutter, a jack mounted for swinging movements in planes at right angles to each other adapted to hold a lasted shoe for presenting the heel breast to the cutter, and a swinging clamp device in said 90 jack adapted to engage the heel for clamping the shoe upon said jack.

13. In a machine of the class described, adapted to trim the heel breasts of boots and 95 shoes, a rotary cutter, a jack mounted for swinging movements in planes at right angles to each other adapted to hold a shoe exposing the heel and sole, and for presenting the heel breast to the cutter, templet devices on said jack to control the line of 100 trim when the heel breast is moved against said cutter, and a stationary guard partially covering said cutter against which the shank of the shoe is brought to limit a motion of the jack in a work feeding direction. 105

14. In a machine of the class described, adapted to trim the heel breasts of boots and shoes, a rotary cutter, a jack mounted for swinging movements in planes at right angles to each other adapted to hold a shoe, 110 a swinging heel clamp on said jack, and a templet carried by said clamp defining a line of heel breast trim for limiting and guiding the movement of the jack relative to said cutter.

15. In a machine of the class described, adapted to trim the heel breasts of boots and shoes, a rotary cutter, and a jack mounted for swinging movements in planes 120 at right angles to each other adapted to hold a lasted shoe, having a yieldable post to receive the last, a rest to receive the toe of a lasted shoe, and a heel clamp to engage the heel for rigidly holding the shoe upon the last. 125

16. In a machine of the class described, adapted to trim the heel breasts of boots and shoes, a rotary cutter, a jack mounted for swinging movements in planes at right angles to each other adapted to hold a lasted 130

shoe for presenting the heel breast to the cutter, and treadle means for moving said jack toward and from the cutter.

17. In a machine of the class described, adapted to trim the heel breasts of boots and shoes, a rotary cutter, a jack mounted for swinging movements in planes at right angles to each other adapted to hold a lasted shoe for presenting the heel breast to the cutter, a swinging clamp device in said jack adapted to engage the heel for clamping the shoe upon said jack, and templet means adjustably mounted on said clamp, adapted to engage an abutment concentric with the axis of said cutter for controlling the line of heel breast trim.

18. In a machine of the class described, adapted to trim the heel breasts of boots and shoes, a rotary cutter, a universal motion jack adapted to hold a shoe exposing the heel and sole, and for presenting the heel breast to the cutter, a clamp on said jack for engaging the heel, templet devices carried by said clamp to control the line of trim when the heel breast is moved against said cutter, and a stationary guard partially covering said cutter against which the shank of the shoe is brought to limit a motion of the jack in a work feeding direction, and against which the shoe is rocked for edge trimming.

19. In a machine of the class described, adapted to trim the heel breasts of boots and shoes, a rotary cutter, and a universally movable jack adapted to hold a lasted shoe for bringing the shoe heel to said cutter comprising a lever, a saddle member fulcrumed upon said lever, swinging in a direction corresponding to said lever, a jack member fulcrumed upon said saddle, swinging in a lateral direction, and means for locking said parts together as a unit or separately one to the other.

20. In a machine of the class described, adapted to trim the heel breasts of boots and shoes, a rotary cutter, and a universally movable jack adapted to hold a lasted shoe for bringing the shoe heel to said cutter, a stationary guard for partially covering said cutter at a point intervening the shank of the shoe and said cutter, said jack comprising a lever, a saddle member fulcrumed upon said lever, swinging in a direction corresponding to said lever, a jack member fulcrumed upon said saddle, swinging in a lat-

eral direction, and means for locking said parts together as a unit or separately one to the other.

21. In a machine of the class described, adapted to trim the heel breasts of boots and shoes, a rotary cutter, a jack mounted for swinging movements in planes at right angles to each other to present the heel breast to said cutter, in combination with means to hold the heel breast and cutter alined in operative position during the continuous action of said cutter.

22. In a machine of the class described, adapted to trim the heel breasts of boots and shoes, a rotary cutter, a universally movable jack to present the heel breast to said cutter, means to produce a relative predetermined movement of the shoe and cutter, in combination with shoe engaging means to oscillate the jack and maintain the same alined during the continuous movement of the cutter relatively with the shoe, and during the action of the cutter.

23. In a machine of the class described, adapted to trim the heel breasts of boots and shoes, a rotary cutter, a jack mounted for swinging movements in planes at right angles to each other adapted to present the heel breast to the cutter, and a combined heel engaging clamp and guide to hold said shoe in cutter-engaging position.

24. In a machine of the class described, adapted to trim the heel breasts of boots and shoes, a rotary cutter, a jack mounted for swinging movements in planes at right angles to each other adapted to present the heel breast to the cutter, and a combined heel engaging clamp and guide, said clamp having a pair of guides extending on each side of the heel.

25. In a machine of the class described, adapted to trim the heel breasts of boots and shoes, a rotary cutter, a jack mounted for swinging movements in planes at right angles to each other adapted to present the heel breast to the cutter, and a combined heel engaging clamp and guide, said clamp having a pair of guides extending on each side of the heel, and means connecting said guides.

In testimony whereof, I have signed my name to this specification.

LOUIS G. FREEMAN.
